UNITED STATES PATENT OFFICE.

LOUIS GODDU, OF WINCHESTER, MASSACHUSETTS.

SOLE CHANNELING AND ROUNDING MACHINE.

SPECIFICATION forming part of Letters Patent No. 687,683, dated November 26, 1901.

Application filed January 11, 1899. Serial No. 701,835. (No model.)

To all whom it may concern:

Be it known that I, LOUIS GODDU, of Winchester, county of Middlesex, State of Massachusetts, have invented an Improvement in Sole Rounding and Channeling Machines, of which the following description, in connection with the accompanying drawings, is a specification, like characters on the drawings representing like parts.

10 The present invention relates to improvements in machines of the above class; and it consists of certain new and useful improvements in the form and arrangement of parts hereinafter more fully pointed out in this specification and defined in the claims.

15 A preferred form of my invention is illustrated in the accompanying drawings, in which—

Figure 1 shows a front elevation. Fig. 2 is a much-enlarged detail showing part of the upper, sole, and welt of a shoe with the rounding and channeling knives to illustrate their method of operation. Fig. 3 is a left-hand side elevation of the working parts of the machine referred to in Fig. 1. Fig. 4 shows a portion of the holder in section, together with the channel-knife carrier, it also being in section, and the channel-knife and part of the rounding-knife, said section being on the line 20 α , Fig. 5. Fig. 5 is a partial front elevation of the holder looking at it in the direction of the arrow, Fig. 4, together with the channel-knife carrier and channel-knife. Fig. 6 is a top view of the parts shown in Fig. 5. Fig. 35 7 shows the rest removed. Fig. 7^a shows the channel-knife block or carrier detached, the knife being omitted. Fig. 7^b shows the channel-knife detached. Fig. 8 is a section on the line x' , Fig. 1, a part of a shoe on its last being represented to illustrate its position during the operation of rounding and channeling the sole. Fig. 9 is a detail showing the spring acting on the end of the sliding and locking rod, to which is attached the channel-knife block or carrier. Fig. 10 shows a partial right-hand end elevation of Fig. 8, chiefly to illustrate the stop for determining the forward position of the bar or slide g^6 under the action of its spring h .

40 Referring to the drawings, A' represents a head suitable to support the working parts of the machine and conveniently provided

with a depending shank A, adjustably supported in a column A², as is usual in certain types of sewing-machines and other classes 55 of column-machines. The head A' is provided with suitable bearings at a to receive the main shaft B, which may be conveniently provided with a balance-wheel B' and driven by a pulley B². In connection with the pulley B², I have illustrated a loose pulley B³ and a suitable belt-shipper B⁴, provided with a handle B⁵, by which the operator can readily shift the belt. The shaft B carries a cam-disk C, upon which are formed two cam-grooves 60 c and c'. (See Figs. 1 and 8.)

65 Mounted in suitable bearings a^2 on the head A' is a short shaft b, upon which is fulcrumed an elbow-lever b', one arm b³ of which carries a cam-roll b⁴, which engages the cam-groove c on the disk C, the other arm b² being provided with a segmental gear, which meshes with the segmental gear d⁴ on the rounding-knife segment d. The rounding-knife segment consists of a segmental slide 70 mounted in a suitable race or groove a⁴ in the head A', and the rounding-knife d³ is secured thereto in any suitable manner, conveniently by means of the plate d' and set-screws d². Upon the periphery of the segment d is formed the gear d⁴, the arrangement being such that a rotation of the disk C gives the rounding-knife d³ a rapid oscillatory movement, as usual in this class of machines, the cam-groove c, however, being so formed 75 that there is a slight dwell between each complete oscillation of the knife d³.

80 To guide and support the work against the action of the knife d³, I have provided a combined work-support and crease-gage e, which 85 engages the crease between the upper and welt and supports the welt against the action of knife d³. Preferably the gage is so arranged as to be movable about an axis at right angles, or nearly so, to the line of feed. 90 The advantage of this arrangement is that in following the curved contour of the welt the gage will conform thereto, so that it will always afford a firm support for the welt, thus insuring a clean and even cut. To permit 95 the movement of the combined work-support and gage e, above referred to, it is provided with a rigid shank e', (see dotted lines, Figs. 1 and 8,) which enters a socket in the arm e²,

- fixed rigidly to the head A', conveniently by the bolt 2. (See Figs. 1 and 8.) The shank e' has an annular groove, (shown in dotted lines, Fig. 1,) which is entered by a screw e², said 5 screw acting to retain the shank e' in the arm e^x, yet permitting it to oscillate somewhat in a plane at right angles to the line of feed, which in the machine in the drawings is a vertical plane.
- 10 The lower edge of the combined work-support and gage e is preferably rounded and beveled to permit it to accurately engage the crease, and a throat e³ is formed therein, which the knife d³ enters after penetrating 15 the stock.
- 15 The machine of the drawings is provided with a tipping channel-knife block, which, broadly speaking, is a well-known device in this art, but in the construction of which I have 20 made certain improvements which I consider to be my invention and which greatly improve the operation of the device.
- 25 As shown, the channel-knife block or carrier is substantially semicylindrical, preferably, however, having its working face cut away or beveled in opposite directions, as shown at f⁶, Figs. 4 and 7^a, so that the face of the block may contact with and follow the variations in the face of the sole. The channel-knife block or carrier is provided with a semicylindrical hub f⁵, and upon each of its sides are formed a series of curved ridges f⁴, concentric with the hub f⁵, which engage a series of grooves formed in the open-faced cylindrical pocket in which the block or carrier is mounted and which is formed at the lower 35 end of an arm g.
- 30 The engaging grooves and ridges above described in connection with the hub f⁵ serve to keep the block or carrier f² in its carrying-pocket, while permitting it to turn freely, thus providing a support for the block or carrier not subject to such wear as will render the knife inaccurate in its operation owing to the 40 looseness of its support. The channel-knife is shown at f and may be conveniently provided with a shank f⁷, which is fitted to a hole in the carrier f² and clamped therein by a set-screw f⁸ or other suitable means.
- 45 The block or knife carrier f² is slotted, as at f⁹, above the knife, and the arm g is also slotted, as at g³, said slots affording a passage-way for the rounding-knife as it moves toward and from the work. It will be noted that the 50 block or carrier f² extends above the knife d³ and that its upper portion bears upon the sole above the line of cut of the rounding-knife d³, and I regard this as a novel and important feature of my invention, since the 55 work is thus supported against the retracting as well as the cutting action of the knife, which insures a clean cut and avoids any tendency to separate the sole from the welt.
- 60 To keep the knife-block f² pressed against the sole, the arm g is secured conveniently by the bolt g⁵ to one end of a shaft g⁶, which is extended through the head A' and is free to oscillate and slide in suitable bearings therein. Against the end of the shaft g⁶ bears a spring h, suitably held by a set-screw h' in 70 a lug or projection h⁴ on the head A'. This spring is of sufficient strength and normally acts to keep the arm g, with its block or carrier f², pressed against the work lying against the work-support and gage e. The shaft g⁶ is conveniently provided with a suitable pin or projection g⁸, which meets a shoulder g^{8x} on the head A' and limits the extent of movement of the arm g and the block f² toward the work-support and gage e. 75
- 80 In the machine of the drawings the channeling-knife f is given a rapid oscillatory movement in the line of feed, as is usual in this class of machines, and to provide therefor an arm g¹⁰ is secured to the shaft g⁶, which at its upper end carries a cam-roll g¹², which engages the cam-groove c', formed in the periphery of the disk C.
- 85 To retract the channel-knife block or holder, I have provided a rack g⁹ on the shaft g⁶, which is engaged by a segmental gear formed on the elbow-lever m, pivoted at m' on the head A'. The lever m is connected with a suitable treadle by the rod m².
- 90 To aid the operator when rounding and channeling a sole designed to have a Scotch or Baltimore edge, I have provided a rest n, which is so placed as to enable the operator to press the shoe against it and properly guide it until the machine has finished operating 100 on the extended edge portion, which would not be properly formed by holding the shoe to the crease-gage.
- 95 As shown, the rest n is located on the side of the rounding-knife toward the trimmed portion of the sole, and consists, preferably, of a finger projected from a shank (see Fig. 7) which is secured to the arm e^x, preferably by the set-screw n', so as to be vertically adjustable. The finger above referred to projects in position to engage the trimmed edge of the sole when it is desired to tip the shoe to provide for a variation in the width of the edge. 105
- 110 It will be noted that the rest n is located to one side of the path of movement of the rounding-knife, and when the shoe is tipped about the rest as a center the tipping center of the shoe is changed, and thus the position of the line of cut is changed and thrown toward or away from the medial line of the sole, thus producing a variation in the projection of the sole edge. 115
- 115 The operation of my invention will be fully understood from the foregoing description of the construction and mode of operation of its several elements.
- 120 I therefore claim as novel and desire to secure by Letters Patent of the United States—
- 125 1. In a rounding and channeling machine, the combination with a shaft and a bearing for the same, of an arm rigidly secured to 130

- 5 said shaft, a knife-block mounted in said arm and carrying a channeling-knife, a work-support, means acting normally to move the shaft longitudinally in its bearing to hold the work against the work-support, and means for oscillating the shaft, substantially as described.
- 10 2. In a rounding and channeling machine, the combination with a shaft and a bearing for the same, of an arm rigidly secured to said shaft, a knife-block mounted in said arm and carrying a channeling-knife, a work-support, and means for oscillating the shaft to impart to the channeling-knife a vibratory movement, substantially as described.
- 15 3. In a rounding and channeling machine, the combination with a segmental slide, of a rough-rounding knife carried thereby, a guideway for said slide, and means for oscillating the slide in the guideway, substantially as described.
- 20 4. In a rounding and channeling machine, the combination with rounding and channeling knives, of suitable guides or gages for controlling the position of the shoe, and a rest at one side of said knives normally out of contact with the shoe forming a support about which the shoe may be tipped to vary the width of the edge left by the rounding-knife, substantially as described.
- 25 5. In a rough-rounding and channeling machine, the combination with rounding and channeling knives, of suitable gages or guides for positioning the shoe, and an edge rest at one side of said knives, normally out of contact with the edge of the shoe and into contact with which the trimmed edge of the shoe may be brought and about which the shoe

may be tipped to vary the width of the edge, substantially as described.

6. In a rounding and channeling machine, 40 the combination with a segmental slide provided with a rack, a rounding-knife carried by said slide, a guideway for the slide, a bell-crank lever carrying a segmental gear meshing with the rack, and means for actuating 45 the lever, substantially as described.

7. In a machine for channeling boots and shoes on the last, the combination with a channel-knife block mounted to tip on an axis substantially parallel with the line of feed, of 50 a channeling-knife carried thereby, and a combined work-support and crease-gage mounted to tip on an axis at right angles to the line of feed, substantially as described.

8. In a rough-rounding and channeling machine, the combination with the rounding-cutter, of a crease-gage located to engage the work in line with the path of movement of the rounding-cutter and an edge rest located to one side of the crease-gage, substantially 55 60 as described.

9. In a rough-rounding and channeling machine, the combination with an oscillating and longitudinally-movable shaft, of an arm mounted on said shaft, a channel-cutter supported by said arm, and means to actuate said arm, substantially as described.

In testimony whereof I have signed my name to this specification in the presence of two subscribing witnesses.

LOUIS GODDU.
